UNITED STATES PATENT OFFICE.

RUFE F. CHRISMAN, OF NASHVILLE, TENNESSEE, ASSIGNOR OF ONE-HALF TO
EDWARD W. REED, OF NASHVILLE, TENNESSEE.

ADJUSTABLE SUPPORTING-BASE FOR PRINTING-PLATES.

1,240,315.

Specification of Letters Patent. Patented Sept. 18, 1917.

Application filed February 15, 1916. Serial No. 78,497.

To all whom it may concern:

Be it known that I, RUFE F. CHRISMAN, a citizen of the United States, residing at Nashville, in the county of Davidson and 5 State of Tennessee, have invented certain new and useful Improvements in Adjustable Supporting-Bases for Printing-Plates, of which the following is a specification.

This invention relates to supporting bases 10 for electro type plates, and more particularly, has for its object the provision of a supporting base of the character described, which may be adjusted to accommodate plates varying in size.

15 A primary object of the invention is to provide a novel device of the character described, easily manipulated, simple in construction, efficient in operation, and strong and durable in use.

20 A further object of the invention, resides in the provision of a device, which is constructed from a plurality of units or sections and which, is adjustable, due to the construction and arrangement of the various 25 units.

A still further object of the invention, resides in adjustable clamping members, which are so arranged as to be readily accessible to the user, and whereby the same may be adjusted 30 into engagement with the plate to be held thereupon.

A still further object, resides in supplying the various units with recesses or pockets, adapted to receive retaining members so that 35 a plurality of plates may be supported upon the base.

Another important characteristic of the invention, lies in the novel construction of the means for locking the supporting base 40 in its adjusted position.

Among the advantages accruing from this construction, it may be mentioned that the device may be easily cleaned, due to the simple construction, that it occupies but little 45 space, due to the compact arrangement, also by the movable clamps arranged on the supporting base a hair line register is made possible, further, the device may be assembled by an apprentice and still further, it 50 may be lifted as though it were a single piece, consequently enabling changes to be made quickly and easily.

Other improvements and novel details in the construction and arrangement of the 55 various parts of the apparatus will be

brought out more in detail in the description to follow, which, for a clear understanding of the invention should be considered in connection with the accompanying drawings forming a part hereof, and wherein is disclosed for the purpose of illustration, convenient and satisfactory embodiments of the invention. 60

In the drawings:

Figure 1 is a plan view of the device 65 showing the same in an assembled condition,

Fig. 2 is a transverse section taken on line 2—2 of Fig. 1,

Fig. 3 is a view in perspective of one of the units, which constitutes one end of the 70 device,

Fig. 4 is a view in perspective of a corresponding unit which is adapted to mesh or telescope with the construction as shown in Fig. 3, 75

Fig. 5 is a view in perspective illustrating the unit which constitutes the remaining ends of the device,

Fig. 6 is a view in perspective showing the element which is adapted to telescope 80 therewith, with the adjustable clamping member removed.

Fig. 7 is a view in perspective of an element which is used for filling in the construction, 85

Fig. 8 is an intermediate element, showing the clamping member removed,

Fig. 9 is a view in perspective showing its corresponding part,

Fig. 10 is a perspective view of a unit for 90 filling in purposes,

Fig. 11 is a side elevation partly in section of Fig. 7 illustrating the mode of fastening plates thereto, and the fastener,

Fig. 12 is a view showing the locking bar, 95

Fig. 13 illustrates the movable clamping member in front and side elevation,

Fig. 14 illustrates the adjustable screw in front and side elevation, and

Fig. 15 is a view showing a preferred 100 form of tool for operating the adjustable screw.

Referring now more particularly to the drawings, wherein like reference characters designate corresponding parts throughout 105 the several views, it may be said for the purpose of convenience, that the various units or sections shall be referred to independently of each other and shall then be further described when in assembled con- 110

dition. 1 is a section adapted to constitute one of the ends of the device, when in assembled condition, the same being provided with a plurality of arms, generally numbered 2, the sides of which are provided with a series of openings 3, the openings in the outer arm being counter-sunk so as to readily receive the locking means. Arranged upon one side of the section 1 is provided 10 a stop portion 4, for the purpose of receiving one end of a plate to be supported thereby. 1' is a section having a head portion, which portion is provided with a plurality of arms generally numbered 2', which correspond in size and shape to the arms of the sections 1. 3' is a series of openings arranged in each of the arms and adapted to register the openings in the arms of the section 1, and 4' is a projection or stop, for the purpose of receiving one end of the plate being supported upon the base.

In Figs. 5 and 6 I have illustrated those sections, which constitute the remaining end of the supporting base, and in this particular construction, I provide sections 5 and 5', the section 5 being provided with a plurality of arms 6 having arranged in the sides thereof a series of recesses 7. 8 is a slidable clamping member provided with notched portions 9 which are adapted to receive the guiding strips 10 arranged in the head of the section 5. 11 is a screw having arranged in the head thereof, a plurality of channel ways 12 which are provided to receive means 35 whereby the same may be turned. The screw 11 is passed through the clamping member and into a threaded recess arranged in the head portion, whereby, the clamp may be slidably adjusted. The corresponding section 5', better illustrated in Fig. 6 is constructed identical with the section 5, with the exception, that the head portion is arranged upon the opposite end thereof. In the section, the head 5' is provided with a 40 plurality of arms 6' having opening 7' arranged therein and adapted to register with the openings 7 of the section 5. The head is provided with a recessed portion having formed therein guiding strips 10' to receive a clamping member 8, and the screw threaded recesses 12, for the purpose of receiving a screw similar in construction to the one as designated at 11 in Fig. 5.

13 are sections, which act as fillers, the 55 sections being provided with the usual head portion, having formed therein, apertures 13' for the purpose of allowing the passage of the clamping screw 11 of the adjoining section therethrough, and having an arm 14 formed thereon, provided with a series of openings 15 adapted to register with the openings in the sections heretofore described, for the purpose of admitting the passage of a locking bar therethrough. Arranged in the top face of the arm 14, are

a plurality of recesses 16 preferably threaded upon their interior, which construction is better illustrated in Fig. 11, and are adapted to receive screw threaded stops 17 formed with an elongated head 18.

19 is a section placed intermediate the two end sections and is provided with a plurality of arms 20 having the usual openings 21. The head portion of the section 19 is provided with a recessed end 22, having arranged therein the guiding strips 23, for the purpose of receiving the clamping structure 8 and 11, and 24 is an opening interiorly threaded for receiving the screw 11. 19' is a corresponding section provided with 80 arms 20' adapted to be received or to telescope with the arms 20 of the section 19. Each of the arms are provided with a series of openings 21' similar to those illustrated in the arms 21, and are so positioned as to register therewith, and the ends of the arms are provided with recessed portions 24' so as to allow for the passage of the screw 11 therebetween. Formed upon one end of the head portion 19' is a projection or stop 25 for the purpose of receiving one side of the plate to be supported thereby.

26 is a section, which serves as a filler, the same being provided with arms 27, the arms having arranged therein a series of recesses 95 28. The section is provided with a corresponding section 26 identical therewith in construction and adapted to telescope with the same.

29 is a bar of a shape, conforming with the 100 openings, arranged in the sides of the arms and having a head portion 30, and adapted to be passed therethrough, in order that the various sections may be held together in an adjusted position.

31 designates a tool having provided thereon end portions 32 which are adapted to engage the channel ways or grooves 12 in the head of the screw 11 so that the same may be turned.

Coming now to the assembling of the device and the operation thereof, the sections 1 and 1' with the arms 2 and 2' are adapted to telescope with each other and to form one end of the supporting base. The sections 5 and 5' with their arms 6 and 6' are adapted to telescope with each other and to form the remaining end of the supporting base. Arranged adjacent the sections 5 and 5' are positioned a plurality of filler sections 13, 120 which are followed by the intermediate clamping sections 19 and 19', these sections being followed by filler sections 13. Assuming that a single plate is to be supported by the base, and that the same is of greater 125 width than the base, that is, when the base is in its contracted position, the various sections are extended until the proper or approximate width has been reached, the side openings 3, 3', 5, 5', 15, 21, 21' and 28 are 130

registered and the locking bar 29 is passed therethrough so that the sections will be securely held in their adjusted position. The plate is then placed upon the base, and 5 the movable screw actuated clamping members 8 are adjusted into engagement with the plate, so as to force the same against the various projections or stops arranged upon their corresponding sections, whereby, the 10 plate may be securely fixed to the base. If it is desired to support a plurality of plates upon the base, and to so arrange the same as to allow for margins, the screw threaded stops 17 are inserted into the proper screw 15 threaded recesses 16 and serve as abutments for the adjoining edges of the plates.

It is to be understood, that the filler sections 13 and 26 may be used at will by the operator and if necessary, the device may be 20 used without the same. Further, I do not wish to limit the invention to the use of a specific number of intermediate clamping members but desire to have it known, that any number thereof may be used as conditions or preference may dictate.

Attention is directed to the fact that the clamping sections such as designated at 20, shown to advantage in Fig. 8, may be meshed or telescoped instead of using the 30 complementary sections as 19' thus affording a supporting base wherein the clamps can be used on one or both sides as conditions or preferences may dictate, and which forms one of the essential features of the 35 present invention.

In accordance with the provisions of the patent statutes, I have described the principle of the invention, together with the construction which I now consider to represent 40 the best embodiment thereof, but it will be apparent to persons skilled in the art, that different arrangements of the parts from those herein shown and described, for producing the desired results, may be employed, 45 together with mechanical equivalents of some of all of said parts.

Having thus described the invention, what I claim is:—

1. An extensible supporting base, including a plurality of telescoping sections certain ones thereof having fixed abutments, 50 movable abutments arranged on others of the sections, all of said sections having a plurality of registerable openings arranged in

the sides thereof, a locking bar adapted to 55 pass through said openings, and filler sections having pin receiving openings in the upper surfaces thereof.

2. In an extensible supporting base, the combination with a telescoping section having an angularly recessed head provided with a threaded counter bore, said head having a plurality of fingers, ribs formed in the annular recess, a slideable abutment having a wearing base and notches movable on the 60 ribs, and an adjusting screw passing through the abutment into the threaded counter bore whereby the slideable abutment may be adjusted.

3. In a device of the character described, 70 the combination of a plurality of clamping sections having end-wise slideable and inter-engageable fingers, a fixed stop on certain of the sections, an adjustable stop on the co-acting ones of the sections, all of said interchangeable fingers having a series of openings adapted to align, a connecting rod adapted to enter the aligned openings to prevent end-wise disengagement of the fingers, end clamping sections having fixed and adjustable stops respectively, and interchangeable filler members arranged to be located between the respective clamping members.

4. In a device of the character described, 80 the combination of an end-wise and laterally expansible base for electro-types, including opposed clamping members having a plurality of laterally slideable and inter-engageable fingers, fixed and adjustable stops on the respective clamping members for engaging the sides of the electro-type, fixed and adjustable stops on others of the clamping members for engaging the electro-type end-wise, filler members arranged to be interposed between the respective clamping members 85 said filled members having fingers the fingers of the filler members and the clamping members having openings, and a key rod adapted to be projected into the openings 90 to prevent the lateral disengagement of the 100 fingers.

In testimony whereof I affix my signature in presence of two witnesses.

RUFÉ F. CHRISMAN.
